CENTRIFUGAL EXTRACTOR

Filed Dec. 31, 1928

UNITED STATES PATENT OFFICE

EMANUEL J. PERRY, OF NEW BEDFORD, MASSACHUSETTS, ASSIGNOR TO THE AMERICAN LAUNDRY MACHINERY COMPANY, OF CINCINNATI, OHIO, A CORPORATION OF OHIO

CENTRIFUGAL EXTRACTOR

Application filed December 31, 1928. Serial No. 329,510.

This invention relates to underdriven extractors, its object being to simplify and improve the basket mounting and driving means in a manner to improve the lubrication system and enable the basket to be readily removed from and applied to its supporting parts.

In the drawings, Fig. 1 is a sectional elevation through one arrangement embodying the invention; Fig. 2 is a detail sectional elevation of the roller bearing on a larger scale; and Fig. 3 is a section as in the horizontal plane of line 3—3, Fig. 1.

The relatively stationary curb 1 is suspended by three rods 2 from the tops of posts or columns 3 with universal mountings 4 at top and bottom, all to permit precession, as is usual. At one side said curb has a bracket 5 to support suitable driving means, such as the motor 6.

20 In the curb is rigidly mounted a non-rotatable post, pillar or spindle 7 around which the basket turns. The basket, marked 8, has the usual foraminous outer wall 9 and at its center is provided with an upstanding sleeve 10 telescoped over the post 7. On the spindle are secured upper and lower inner bearing races 11, 12 cooperating with bearing rollers 13 lying between them and the outer races 14, 15, the upper bearings taking the radial and 25 the lower bearings the vertical strains. By removing a detachable cap 16 from sleeve 10 and taking off the unit 17 the basket may be lifted off from spindle 7, as will be readily understood.

30 At the bottom of the spindle the curb carries an annular shield or guard 18 (Fig. 2) entering an opening in the basket bottom. Lubricant is supplied to spindle bearings through the plugged opening 19, traveling 35 down along the spindle past the bearings to its bottom, when it is held from escape by said guard.

Attached to the bottom of the basket is a pulley 20 around which travel drive ropes or 40 belts 21 which pass through a curb opening 1a to the motor pulley 22. Said pulley 20 is of driven form and also serves as the brake drum, its inner surface being gripped by suitable expanding friction brake mechanism, 45 marked generally 23 and including an actu-

50 ator 24 operated by a shaft 25 having an arm 26 below the curb where it may be connected to any suitable controlling or operating mechanism such as the lever 23a. The details of the brake mechanism however may be of any suitable or preferred description and form 55 no part of the invention and have been more or less conventionally illustrated in Fig. 3.

Pulley 20 lies in an annular recess 27 formed within a depending portion of the 60 curb around the post 7, the wall of said portion, of course, including the belt opening 1a. Also the curb at its bottom has its floor sloping outwardly to a channel 28 leading to the drain 29, to thereby conduct the extracted 65 liquid to an outlet and away from recess 27.

This arrangement simplifies the construction and assembly of the basket and spindle, and also the lubrication problem is to a large extent reduced to very simple form.

Having described my invention, I claim:

In an extractor, a frame, a curb frame, a curb carried thereby and having an upwardly dished bottom with a central opening, universal supporting linkage between said curb 75 and curb frame, a hollow boss secured to said bottom at said central opening and provided with a lateral belt drive opening, a shaft support carried by said boss and projecting upwardly to a point substantially flush with the upper surface of said bottom, a shaft in 80 said support and projecting upwardly into said curb, a basket, a central sleeve carried thereby, upper and lower bearing structures between said sleeve and said shaft, a pulley 85 secured to the bottom of said basket and surrounding said shaft support, a motor mounted on the curb frame, and a belt drive between said motor and said pulley.

In testimony whereof I hereby affix my signature.

EMANUEL J. PERRY.
